UNITED STATES PATENT OFFICE.

WILLIAM A. MONTAGUE, OF DULUTH, MINNESOTA.

DESIGN FOR A SPOON.

SPECIFICATION forming part of Design No. 22,660, dated August 1, 1893.

Application filed March 18, 1893. Serial No. 466,717. Term of patent 3½ years.

To all whom it may concern:

Be it known that I, WILLIAM A. MONTAGUE, a citizen of the United States, residing at Duluth, in the county of St. Louis and State 5 of Minnesota, have invented a new and original Design for Spoons, of which the following is a specification.

The invention relates to a new and original design.

10 The object of the present invention is to provide an ornamental and attractive spoon; and the essential feature resides in a spoon handle having an ornamental obverse with a scene representing the fleet of Columbus and 15 marginal ornamentations and scrolls, and having a reverse with a representation of the head of Columbus, a banner and ornamental leaves and marginal ornamentations and scrolls.

20 In the drawing—Figure 1 is an elevation of the obverse of a spoon showing my original design. Fig. 2 is a similar view of the reverse of the same.

Referring to the drawings, 1 designates a spoon handle having its obverse 2 ornamented with raised scroll work, and bearing within the scrolls a scene representing the fleet of Columbus. The reverse 3 has an ornamental irregular outline, and bears a representation of the head of Columbus, a banner, and an 30 ornamental strip of leaves arranged on the narrower portion of the handle. The spoon handle has ornamental scolloped edges and is provided with marginal ornamentations and scrolls surrounding the above described 35 representations.

What I claim is—

The design for a spoon, substantially as shown and described.

In testimony that I claim the foregoing as 40 my own I have hereto affixed my signature in the presence of two witnesses.

WILLIAM A. MONTAGUE.

Witnesses:
